UNITED STATES PATENT OFFICE.

BENJAMIN EUGENE CUNDIFF, OF HALLOWELL, KANSAS.

UMBRELLA.

1,218,526.

Specification of Letters Patent.

Patented Mar. 6, 1917.

Application filed June 3, 1916. Serial No. 101,568.

To all whom it may concern:

Be it known that I, BENJAMIN E. CUNDIFF, a citizen of the United States, residing at Hallowell, in the county of Cherokee and 5 State of Kansas, have invented new and useful Improvements in Umbrellas, of which the following is a specification.

This invention relates to umbrellas and has particular application to a folding umbrella. The chief characteristic of this invention resides in the provision of a device of this character having sectional telescopic ribs and a sectional staff whereby the umbrella may be collapsed or folded into compact form to facilitate the transporting of 15 the same from place to place.

Another object of this invention is to provide a device of this character having means for locking the telescopic ribs in extended position and thus preventing the accidental telescoping of the ribs when in active position.

Another object of this invention is to provide a device of this character which contains the desirable features of simplicity, 25 efficiency and durability and furthermore a device which may be conveniently applied to an umbrella of any common construction without giving additional weight to the umbrella.

Other objects of the invention will appear as the specification is read in connection with the accompanying drawings, in which;—

35 Figure 1 is a sectional view of an umbrella constructed in accordance with my invention.

Fig. 2 is a view of the umbrella collapsed, or closed.

40 Fig. 3 is an enlarged detail view of a portion of one of the ribs and its connection with one of the stays.

Fig. 4 is a transverse section of Fig. 3.

Referring to the drawings in detail, my 45 invention comprises a staff A which is formed of two sections, 1 and 2 respectively, the section 2 being provided with a screw threaded extension 3 which is adapted to lie within a screw threaded socket 4 formed 50 on the adjacent end of the section 1 whereby the sections may be detached to permit the shortening of the staff as will be understood.

Pivottally mounted upon the staff A are 55 my improved form of ribs generally indicated as at B to which are pivottally con-

nected the stays C. In this embodiment of my invention I have shown the ribs B each formed of two sections 5 and 6 respectively, the latter section 6 being formed of a single sheet of material bent longitudinally upon itself in substantially cylindrical formation. The opposite longitudinal edges of these sections 6 are arranged in parallel spaced relation to each other to provide the longitudinally extending slot 7, the outer end of the slot terminating rearwardly of the outer end of the section whereupon the section is compressed as at 8 and provided with the transversely extending opening 9. The cover of the umbrella is secured to these sections 6 by means of the stitching which is adapted to pass through the opening 9 as is the usual way of securing the cover to the ribs. The inner or upper section 5 of the rib is formed of a single length of material which has its inner end pivottally mounted upon the staff in the usual manner while its lower end is adapted to extend into the section 6 as is clearly shown in the drawings. The lower end of the section 5 is provided with a laterally extending stud 10 which is adapted to ride in the slot 7 thus causing both of the sections to assume their proper position with relation to their connection with the cover and staff respectively whereby accidental turning of the ribs will be prevented. The inner end of the section 6 has rigidly mounted thereupon a bracket 11 which is of substantially U-shaped formation, the free ends of which terminate in alined ears 12. This bracket 11 is adapted to snugly engage or partially encircle the inner end of the section 6, the ears 12 receiving a shaft 13 upon which is pivottally mounted the bifurcated end 14 of the stay C. The opposite ends of the stays C are pivottally secured to the movable collar in the usual manner.

The bracket 11 further serves to securely retain a spring clip 15 upon the inner end of the section 6, the clip extending longitudinally of the section and overlying the slot 7. This spring clip 15 is formed of a single piece of resilient metal which has its lower end provided with an opening 16, the latter being so positioned as to receive the stud 10 when the sections are in extended position. Owing to the resiliency of the clip, it will securely hold the stud 10 within the opening 16 and thus prevent longitudinal movement of the section 5, the free end

of the clip being slightly flared outwardly to permit the lifting of the clip to remove the stud when it is desired to collapse the rib as will be understood.

5 When it is desired to collapse the umbrella so that the same will occupy a minimum amount of space and thereby permit the same to be conveniently transported from place to place, the section 2 of the 10 staff is unscrewed and removed thus shortening the length of the staff as will be understood. The studs 10 are now removed from the openings 16 of the clips 15 whereby the sections 5 and 6 are telescoped one 15 within the other. This causes the ribs to occupy about one-half the space that they originally did and thus permits the frame to be collapsed so as to snugly engage the staff A. It will be understood that the 20 cover carried by the ribs will also be folded upon itself so that both the ribs and cover will not extend beyond the section 1 of the staff A. It will thus be seen that I have provided simple and efficient means 25 for causing the umbrella to assume a relatively small space whereby it may be readily packed within a suitcase or trunk and the usual bunglesomeness eliminated.

It is thought from the foregoing taken in

connection with the accompanying drawings 30 that the construction and operation of my device will be apparent to those skilled in the art without further description, and that minor changes in size, shape, proportion 35 and minor details of construction may be made without departing from the spirit and scope of the appended claim.

What I claim is:

In combination, a rib comprising sections, 40 one of said sections being hollow and formed with a longitudinally extending slot, the remaining section being slidably mounted within the first section, a stud formed on said remaining section and riding in said slot, a substantially U-shaped bracket secured to the inner end of the hollow section and partially encircling the same, the free ends of the bracket extending laterally from 45 said section, a spring clip interposed between the bracket and the hollow section 50 and having one end thereof overlying said slot and formed with an opening to receive said stud, and a stay having a bifurcated end pivotally mounted between the free ends of said bracket. 55

In testimony whereof I affix my signature.

BENJAMIN EUGENE CUNDIFF.
